Primary Examiner — Susan Bennett Hattan*Assistant Examiner* — Leanne Was(74) *Attorney, Agent, or Firm* — Knobbe, Martens, Olson & Bear, LLP(57) **CLAIM**

The ornamental design for an optical component, as shown and described.

DESCRIPTION

FIG. 1 is a front, top, and right side perspective view of an optical component;

FIG. 2 is a back, bottom, and left side perspective view thereof;

FIG. 3 is a right side elevation view thereof;

FIG. 4 is a left side elevation view thereof;

FIG. 5 is a front side elevation view thereof;

FIG. 6 is a back side elevation view thereof;

FIG. 7 is a top plan view thereof; and,

FIG. 8 is a bottom plan view thereof.

The features illustrated in phantom line from no part of the claimed design.

1 Claim, 8 Drawing Sheets(56)
